(57) **CLAIM**

The ornamental design for a cutting blade of a weeding device as shown and described.

DESCRIPTION

FIG. 1 is a perspective view of a cutting blade of a weeding device.

FIG. 2 is a bottom plan view of the cutting blade of FIG. 1.

FIG. 3 is a top plan view of the cutting blade of FIG. 1.

FIG. 4 is a rear elevation view of the cutting blade of FIG. 1.

FIG. 5 is a front elevation view of the cutting blade of FIG. 1.

FIG. 6 is a right-side elevation view of the cutting blade of FIG. 1.

FIG. 7 is a left-side elevation view of the cutting blade of FIG. 1; and,

FIG. 8 is an environmental view of the cutting blade of FIG. 1.

Where present, the broken lines shown in the figures depict portions of the cutting blade of the weeding device that form no part of the claimed design.
